Primary Examiner — Catherine Tuttle(74) *Attorney, Agent, or Firm* — Cynthia R. Miller(57) **CLAIM**

The ornamental design for a fragrance bottle, as shown and described.

DESCRIPTION

FIG. 1 is a top, front and right side perspective view of my new design for a fragrance bottle;

FIG. 2 is a front elevation view of the fragrance bottle shown in FIG. 1;

FIG. 3 is a right side elevation view of the fragrance bottle shown in FIG. 1;

FIG. 4 is a rear elevation view of the fragrance bottle shown in FIG. 1;

FIG. 5 is a left side elevation view of the fragrance bottle shown in FIG. 1;

FIG. 6 is a top plan view of the fragrance bottle shown in FIG. 1; and,

FIG. 7 is a bottom plan view of the fragrance bottle shown in FIG. 1.

The broken lines are included for the purpose of illustrating the nozzle outlet that forms no part of the claimed design.
